United States Patent

Des. 239,112
Patented Mar. 9, 1976

239,112

MARKING INSTRUMENT

William E. Marynissen, Old Greenwich, Conn., assignor
to Bic Pen Corporation, Milford, Conn.

Filed Sept. 26, 1974, Ser. No. 509,713

Term of patent 14 years

The term of this patent subsequent to Dec. 16, 1989,
has been disclaimed

Int. Cl. D19—06

U.S. Cl. D19—45

FIG. 1 is a top plan view of a marking instrument showing my new design;

FIG. 2 is a front elevational view;

FIG. 3 is a left end elevational view;

FIG. 4 is a right end elevational view;

FIG. 5 is a front elevational view with the cap deposited on the end remote from the marking end; and

FIG. 6 is a left end elevational view thereof.

I claim:

The ornamental design for a marking instrument, substantially as shown and described.
